UNITED STATES PATENT OFFICE.

ROBERT SANFORD RILEY, OF WORCESTER, MASSACHUSETTS, ASSIGNOR TO RILEY STOKER CORPORATION, OF WORCESTER, MASSACHUSETTS, A CORPORATION OF MASSACHUSETTS.

FURNACE-WALL CONSTRUCTION.

Application filed September 9, 1921. Serial No. 499,508.

This invention relates to a furnace wall construction, more particularly adapted to furnaces equipped with underfeed stokers and operated under forced draft.

- 5 It has been found desirable to supply air under pressure to such furnaces, not only to the tuyère blocks between and at the sides of the retorts, but also to the furnace side walls adjacent the outer retorts.
- 10 It is the general object of my invention to provide a ventilated furnace side-wall of improved construction, in which the parts are easily assembled, and in which worn parts may be easily and cheaply removed and 15 replaced.

It is a further object to provide for even distribution of the air through different parts of the wall. My invention further relates to arrangements and combination of 20 parts, which will be hereinafter described and more particularly pointed out in the appended claims.

A preferred form of my invention is shown in the drawings, in which

- 25 Fig. 1 is a front elevation of a portion of a furnace side-wall constructed in accordance with my invention;
- Fig. 2 is a sectional elevation thereof, taken along the line 2—2 in Fig. 1;
- 30 Fig. 3 is a detail front view of a portion of the back frame;
- Fig. 4 is a detail sectional plan view taken along the line 4—4 in Fig. 2;

Fig. 5 is a partial plan view of one of the 35 side-wall plates, taken in the direction of the arrow 5 in Fig. 6; and

Fig. 6 is a sectional elevation of the plate, taken along the line 6—6 in Fig. 5.

Referring to the drawings, I have shown 40 a portion of a side-wall 10 and parts of certain retorts of an underfeed stoker, these parts comprising a retort side plate 11, rows of tuyère plates 12' arranged in stepped relation between the retorts, and several of 45 the side tuyère blocks 12. At the rear of the retort there is also shown a portion of the usual dump-plate 13.

In the preferred construction, recesses 14 and 15 are formed in the side-wall 10 and 50 a back frame 16 is mounted in the recess 14, this frame being preferably formed as a series of separate sections, extending along the incline towards the front of the furnace.

Each back frame section 16 is provided

55 with lugs or brackets 17 (Fig. 2) fitting over the rear edges of an angle-iron 18 which supports the usual plates 19 at the outside of the tuyère blocks. The frame sections 16 are formed with flanges 20 engaging and positioning the upper edge of the plate 19, and 60 also with top flanges 21 on which the upper portion of the wall is partially supported. The frame sections are also provided with a plurality of outwardly extending lugs 22, 65 preferably arranged in pairs in staggered relation, as clearly shown in Fig. 3, and having aligned openings 22^a therein.

Side wall plates 23 (Fig. 2) are supported by the back-frame sections 16 and are each provided with end flanges 24 (Fig. 4) and 70 with longitudinal flanges or lugs 25, each having two openings 26 therein. The plates 23 are also preferably provided with a series of holes or perforations 28 through 75 which air is admitted to the furnace.

The method of assembling the parts is clearly shown in Figs. 2 and 4, headed fastening studs 30 being inserted through the openings 22^a in the lugs 22 and through the corresponding openings 26 in the flanges 25. The lugs 22 80 are arranged in staggered relation to permit easy insertion and removal of the headed fastening studs for adjacent plates. The headed studs 30 are usually merely dropped into place through the openings in the associated lugs or flanges and may be easily driven out whenever it is necessary to replace worn side-wall plates.

Reference to Fig. 2 will also show that the assembled plates 23 are not in close contact 90 with each other, but that slots or air-openings 32 are left between adjacent plates to admit additional air to the furnace.

Air openings 33 are formed in the end walls 34 of the back-frame sections 16 and 95 the end flanges 24 of the plates 23 are cut away at their rear edges so that they do not obstruct the openings 33. Air is supplied from the usual air-conduits 35 through the recesses 15 to the space between the back-frame sections and the front-plates, the course of the air being indicated by the arrows in Figs. 1 and 2.

An opening or recess 15 is provided for each back-frame section 16 and the openings 100 33 permit transfer of air from one section to another, equally distributing the air through the side-wall plates.

Having thus described my invention, it will be evident that changes and modifications can be made therein by those skilled in the art, within the spirit and scope of my invention, as set forth in the claims, and I do not wish to be otherwise limited to the details herein disclosed, but what I claim is:—

- 5 1. In an underfeed furnace, in combination, underfeed retorts, tuyère plates therebetween, side tuyère blocks for said furnace, a side wall, a frame supported thereby, wall plates detachably secured to said frame above the plane of said side tuyère blocks, said frame and plates defining an air passage, and means to supply air through said passage to said furnace through and around said plates.
- 10 2. In an underfeed furnace, in combination, underfeed retorts, tuyère plates therebetween, side tuyère blocks for said furnace, a furnace side wall having a recess, a frame formed in sections secured to said wall in said recess, a series of wall plates secured to said frame sections above the plane of said side tuyère blocks, said frame and plates defining an air passage, and means to admit air to each section between said frame and said plate, said sections also having connected openings permitting the passage of air between adjacent sections.
- 15 3. In a furnace, in combination, a wall, a frame mounted on said wall and having a plurality of lugs vertically spaced apart on the outer face thereof, a series of wall plates arranged one above the other and having additional lugs rearwardly projecting therefrom, fastening devices effective to connect

associated lugs together, and means to supply air behind said plates.

4. In a furnace, in combination, a wall, a frame mounted on said wall and having a plurality of lugs vertically spaced apart on the outer face thereof, a series of wall plates arranged one above the other and having additional lugs rearwardly projecting from its rear face, associated lugs having aligned openings therein, and headed fastening members positioned in said openings to detachably secure said plates in position.

45 5. In a furnace in combination, a wall, a frame mounted on said wall and having a plurality of lugs vertically spaced apart and in staggered relation on the outer face thereof, a series of wall plates arranged one above the other and having additional lugs rearwardly projecting therefrom and arranged in corresponding staggered relation to the arrangement of the lugs on the frame, fastening devices effective to connect assembled lugs together and means for supplying air 55 behind said plates.

6. In a furnace, a side wall, underfeed retorts, tuyère plates therebetween, tuyère blocks at the side of said furnace, a plurality of flat perforated air admitting wall plates 65 mounted on said wall above the plane of said side tuyère blocks and forming the outer wall of an air passage, and means to supply air behind said plates, said plates being perforated and spaced apart.

70 In testimony whereof I have hereunto affixed my signature.

ROBERT SANFORD RILEY.
